(57) **CLAIM**

The ornamental design for a tree sculpture and candelabrum, as shown and described.

DESCRIPTION

FIG. 1 is a front elevational view of a tree sculpture and candelabrum showing my new design, the rear elevational view being a mirror image thereof;

FIG. 2 is a side view, taken from the left side of FIG. 1;

FIG. 3 is a side view, taken from the right side of FIG. 1;

FIG. 4 is a top plan view thereof; and,

FIG. 5 is a bottom plan view thereof.
